UNITED STATES PATENT OFFICE.

CLEMENT V. HILL, OF TRENTON, NEW JERSEY.

REFRIGERATOR.

SPECIFICATION forming part of Letters Patent No. 414,907, dated November 12, 1889.

Application filed June 21, 1889. Serial No. 315,038. (No model.)

To all whom it may concern:

Be it known that I, CLEMENT V. HILL, of Trenton, in the county of Mercer and State of New Jersey, have invented a new and Improved Refrigerator, of which the following is a full, clear, and exact description.

This invention relates to refrigerators, and has for its object to provide a refrigerator by means of which vessels and receptacles in the refrigerator, and especially bulky jars and tubs, may be readily handled in placing and removing them from the refrigerator, and by means of which also the temperature of the refrigerator will not be affected while the contents of the tub or vessel are being emptied or replenished upon being removed from the refrigerator for the purpose, and the waste of ice prevented.

The invention consists in a refrigerator constructed and arranged as hereinafter described and claimed.

Reference is to be had to the accompanying drawings, forming a part of this specification, in which similar figures of reference indicate corresponding parts in all the views.

Figure 1 is a view of a refrigerator constructed in accordance with this invention. Fig. 2 is a side view thereof in vertical section. Fig. 3 is a plan view of a shelf detached; and Fig. 4 is a detail thereof in position, partly in section and broken away.

In carrying out this invention, a refrigerator 1 of suitable size and shape is provided, having any number of storage-compartments 2 with doors 3. As here shown, the top of the refrigerator is constructed with a grating 4, on which rests the ice 5, and an inclined sheet-metal floor 6, located beneath the grating 4, having a discharge-pipe 7 leading through the side of the refrigerator to carry off the drip from the ice.

In the bottom of one or more of the compartments 2 is located a sliding flat shelf or board 8, having its side edges located and adapted to run in grooves 9, formed, as here shown, by strips 10. To enable the shelf 8 to be easily moved in the grooves 9, friction-rollers 11 are located in the sides of the shelf 8 at its rear end, so as to project upward and downward and bear against the strips 10 of each groove 9, and friction-rollers 12 are located in the bottom strip 10 or bottom of each

groove 9 at its forward end, so as to project upward and bear against the shelf 8. By this means, when the shelf 8 is in closed position or within the refrigerator, as shown in the upper compartment 2 in Fig. 1, and in the lower compartment 2, as shown in Fig. 2, the rollers at the rear end of shelf 8 bear on the strips 10, and the sides of the forward end of shelf 8 rest on the rollers 12. When the shelf 8 is drawn out of the refrigerator, it will rest on and move over the rollers 12, and if a tub of butter rests on the shelf 8 it will be found that the weight will press the shelf 8 down on the rollers 12, and the shelf 8 may be easily drawn with its load over the rollers 12. As that portion of the shelf with the weight on it is carried over and beyond the rollers 12, the weight will cause the rear end of the shelf 8 to be pressed up in grooves 9, and as the rollers 11 bear up against the top and bottom of grooves 9 the further outward movement of the shelf 8 with its load may be easily continued until the shelf 8 reaches the extended position outside of the refrigerator, as shown in connection with the lower compartment 2 in Fig. 1 and the upper compartment 2 in Fig. 2. In this way an unwieldy receptacle, like a tub of butter, may be easily placed in and removed from the refrigerator. When the shelf 8 is drawn out so that the tub of butter or other receptacle rests on the shelf outside of the refrigerator, a sufficient rear portion of the shelf 8 remains inside of the refrigerator in the grooves 9 to support the shelf and the weight resting thereon.

In order that the temperature of the refrigerator may not be affected by the outside warm air rushing into the refrigerator through the opening left by the open door 3 while the tub or vessel resting on the projecting portion of the shelf 8 is being emptied or filled, provision is made for closing the opening of compartment 2. This is effected by means of doors 13, hinged at the sides of the opening inside of the compartment 2 and folding against the sides of compartment 2. The doors 13 are provided with spring-hinges 14, which tend by their tension to throw the doors 13 forward to close the opening of compartment 2. When the shelf 8 is inside of the compartment 2, the doors 13 are held back against the sides of compartment 2 by the

side strips 15 on the top of shelf 8, connected at their rear end by a cross-strip 16, adjacent to which the lower edges of the doors 13 are located when the latter close the opening 5 of compartment 2.

Extending from the side strips 15 to the cross-strip 16 on shelf 8 are mounted curved strips 17, by means of which the doors 13 are permitted to gradually close as the shelf 8 is 10 drawn out, the spring-hinges 14 holding the doors 13 against the strips 17. As the shelf 8 is pushed in the curved strips 17 press against the doors 13 to open them.

The shelf 8 is formed with an aperture 18 15 in its rear and a cut-away portion 19 or an aperture in its forward end, whereby air is permitted to circulate under the shelf 8. The upper edge of the doors 13 is provided with a horizontal flange 13', by means of which 20 the space between the top of the doors is closed, the bottom of the doors abutting close against the strip 16.

It will thus be seen that by means of this invention bulky articles may be readily and 25 easily placed in and removed from a refrigerator, and that while the contents of the compartment are being handled outside of the refrigerator the temperature of the refrigerator will not be affected by the outside 30 air, and the loss of ice arising from the change of temperature caused by admission of the outside air is avoided, thereby effecting a material saving of ice.

Having thus described my invention, I claim 35 as new and desire to secure by Letters Patent—

1. A refrigerator having one or more compartments constructed with a flat shelf having curved guide-strips on its rear end and 40 extending over the bottom of the compartment and movable out of and into the refrigerator through the door-opening of the refrigerator, with guide-supports for the shelf

to hold it in extended position when projected out of the refrigerator, and automatically-closing doors on the inside of the compartment bearing against the guide-strips on the shelf and opened and closed by the movement of the shelf, substantially as described. 45

2. The combination, with a compartment having a door and a sliding shelf movable in and out of said compartment through the door-opening, of an auxiliary automatically-operated closure in the compartment, released upon the outward movement of the shelf, substantially as set forth. 50

3. The combination, with a compartment having a door and a shelf movable in and out of said compartment through said door-opening, of an auxiliary automatically-operated closure in said compartment, released upon the outward movement of the shelf, and extending, when closed, into the path of the inner part thereof, to be opened by the inward movement of the shelf, substantially as set forth. 55

4. In a refrigerator, the compartment 2, with grooves 9 at the bottom of its sides and internal spring-actuated outwardly-closing doors adjacent to the door-opening of compartment 2, in combination with a sliding flat shelf 8, located in grooves 9 and adapted to be projected out of the door-opening, with side strips and curved strips bearing against the internal doors to open and close them, and projecting rollers at the rear of shelf 8, located in the grooves 9, and upwardly-projecting rollers located in the forward part of grooves 9 and bearing against the under side of shelf 8, substantially as described. 70
